UNITED STATES PATENT OFFICE.

SIMON W. WARDWELL, OF PROVIDENCE, RHODE ISLAND.

YARN-CONTROLLER.

SPECIFICATION forming part of Letters Patent No. 752,813, dated February 23, 1904.

Application filed December 5, 1901. Serial No. 84,825. (No model.)

To all whom it may concern:

Be it known that I, SIMON W. WARDWELL, a citizen of the United States, residing at Providence, in the county of Providence and State 5 of Rhode Island, have invented a new and useful Improved Yarn-Controller, of which the following is a specification.

My invention relates to yarn-controllers for textile machinery, and particularly to devices 10 for use on doubling-machines such as are employed in the manufacture of threads.

The purpose of my invention is to provide improved devices for independently regulating the tension on each of the several yarns 15 in a "doubling" means whereby said tension-regulating devices may be quickly and readily threaded without particular care and with the least possible movement and exertion on the part of the operator, and devices to cause the 20 winding to be arrested when a bunch or slab occurs in any one of the several yarns.

The following specification fully sets forth my invention and manner of its operation, and the annexed drawings, forming a part of the 25 said specification, represent, respectively, in—

Figure 1, the front view of a winding-machine fitted for doubling or winding a plurality of yarns together and my new devices applied to said machine; Fig. 2, a side view 30 of the stop-motion of the machine in conjunction with my new device; Figs. 3 and 4, details of the slab-detector; Figs. 5, 6, and 7, details of the tensions and of their arrangement; Fig. 8, a view, partly in section, on the line 11, 35 Fig. 2, showing the arrangement and manner of adjusting the supplies; Fig. 9, a view in perspective of the fixed tension member *d*, showing the thread-groove 23; and Fig. 10, a view in perspective of the movable tension member *c*.

The preferred embodiment of my invention is used in conjunction with stop-motion devices such as are described in my United States Patent No. 598,587, in which several "drop-wires" or "breaking-levers," adapted to engage a rotating fluted roll to arrest the winding, are withheld from such engagement during the winding by the tension of the yarns passing through them. The yarn tension is, 45 however, not applied and controlled by means

of a pad, as in the device described in the above-mentioned patent, but by separate devices applied to each yarn, so that the tension can be adjusted for each individual yarn, thus insuring a uniformity that is not attainable 55 where one adjustment affects all the yarns.

An important feature of my device is the slab-detector, which when a "slab" occurs is moved to act upon the tension device to cause the release of the tension of the yarn, thus affecting the stopping of the winding and without breaking the yarn.

In doubling yarn for the manufacture of threads the maintenance of uniform tension on the individual yarns and the elimination of 60 slubs and motes are essential to a perfect thread product. It is for this class of work that my improvement is particularly devised. For convenience the term "slab" will be employed to designate any abnormal enlargement 65 of the yarn whether it be a bunch of fiber incorporated in the yarn, a large knot, or any similar defect which would cause a bunch in the finished product and which must be removed or remedied by breaking or at least by 70 stopping the yarn. The term "mote" applies only to bits of foreign matter which cling to its surface and can be stripped or removed without stopping or breaking the yarn.

Referring in detail to my invention, the 75 yarn-controller comprises two tension members separable one from the other to receive the yarn and adapted to be pressed toward each other by suitable means to apply friction or resistance to the movement of the yarn. 80 As shown in the accompanying drawings, both members are mounted on a common rod 18, that is supported in the portions 16 and 17 of the bracket *K*. One of the members, *d*, is fixed, secured from turning about the rod 18 by the 85 screw 19 passing through the ear 20 into the bracket *K*. The other member, *c*, is movable, adapted to be swung toward the fixed member *d* by means of weights hung on the arm 15, connected to the member *c*. Each tension member comprises a body portion of grid form, two ears through which the supporting-rod is passed, and a guide portion to receive the yarn and direct it to the grid. The guide portion comprises a narrow edge or rim 21, 90

extending from end to end of the member, bowing outward at its mid-portion and joined at its mid-portion with the body of the member by the tie-piece 22. The bars of the grid portion are of rectangular section with substantially square corners, the latter being just sufficiently rounded to remove any sharpness that might abrade or cut the yarn. They are disposed in such manner that when the two members are mounted together the bars of one member alternate with those of the other, so that when a yarn is passed and pressed between them it is caused to travel in a sinuous path, Fig. 7, causing resistance to its movement and tension on the yarn as it is drawn from the members. The degree of tension imparted depends on the degree of sinuosity of the yarn's path of travel both as regards the amplitude of deflections and their number. For fine yarns the best results are obtained from many deflections of slight amplitude, for the yarn is thus subjected to less strain. As indicated in the term "controller," the members *c* and *d* serve to regulate the tension and control the delivery of the yarn, as well as to apply it. A certain amount of tension is incident to the drag of the yarn on the surface of the supply-package as it is unwound. When this drag is at its minimum, the tension members are pressed tightly together, imparting the maximum amount of tension to the yarn. When an increase in resistance occurs at the supply, the tension members yield, permitting the yarn to straighten and the tension to decrease at the point where the yarn passes through the members. The bars of the grids are made with substantially square corners that they may more certainly engage and knock from the rapidly-moving yarn any motes that may cling to it. Were the bars materially rounded, especially on the edges over which the yarn passes, the motes would not be removed, but would ride over the bars. The bars of one grid do not pass those of the other, their movement being limited by the contact of the two tension members. Hence only a limited degree of tension can be applied. This is desirable in handling fine yarn, especially in work where uniformity of tension on several yarns is the essential end to be attained and not a high degree of tension on individual yarns. The guide portion of each member is so curved from the plane of the grid portion that when the two members are mounted together a flaring trough or channel is formed, into which the yarn may be led in threading and guided to the grid portion, into which it will be automatically drawn, as hereinafter explained. After the yarn has been introduced between the tension members *c* and *d* the latter tend to open slightly and diverge radially from the axis of the rod on which they are mounted. As the yarn delivers from the supply it has a tendency to whip and shiver. The whip of

the yarn, combined with the divergence of the tension members, tends to cause the yarn to shift its position between the latter. To prevent this, a slight groove 23 is formed across the bars of one or both members. This suffices to hold the yarn to resist any tendency to displacement. 70

Of the two standards 16 and 17, which support the members *c* and *d*, one, 16, also supports a guide *f*, through which the yarn is led to the tension members. The other, 17, is of such height that its top and the surface of the guide *f*, over which the yarn draws, align with the groove in the bars of the tension members and serve to insure that the 80 yarn shall in threading be drawn down to the groove and no farther. The guide *f* is preferably formed of wire. As shown in the drawings, it is formed of a loop the sides of which extend parallel for a short distance, then diverge, forming a means for readily threading, of the same general shape as formed by the guides of the tension members, and, finally, return in a reversed curve past the guide-loop as two legs 24 24, which enter appropriate 90 sockets in the projection 16.

Between the guide *f* and the tension members is the detector *a*, consisting of a slotted plate with two ears 10 10, a yarn-slot 11, and a projecting portion 12, as clearly shown in 95 Figs. 3, 4, and 6. The projecting portion 12 is of substantially triangular shape and is formed at an angle with the face of the body 9 and with its extreme portion 13 formed substantially at a right angle to the body 9 aforesaid. The detector is mounted by the ears 10 10 on the rod or pin *g*, which in turn is mounted in the legs of the guide *f*. The extremity 13 is posed in such relation to the tension members that when swung toward them it enters between them, and the inclined portion of the projection 12 forces them apart. When the pressure which rocked the detector is removed, the reaction of the closing tension members forces the detector back to its normal position, where it rests against the loop portion of guide *f*, as shown in full lines, Fig. 2. The entrance to the yarn-slot is rounded and flared, so that it may be readily threaded, and the latter operation is further aided by the close proximity of the detector when in its normal position to the guide *f*. 110

The tension members, guide *f*, and detector *a* are mounted near the top of a bracket *K*. Immediately beneath them is the supply-holder *m*. That the supplies may be replenished as rapidly as possible, it is essential that the supply-holders *m* be in such position and so arranged that the operator may replace empty tubes and bobbins with the least possible movement or exertion. To this end the supplies are raised as high as possible, and the tension devices are also inclined that the operator may lay the yarn in place without the exercise of special care. Their inclination 125 130

also permits the supplies to be raised higher than would be possible were the tension members vertical. The supply is carried at the bottom of the depending arm *k* of the bracket 5 *K* on a spindle *l*, which may be of any form appropriate to the form of supply employed. The spindle *l* is secured in the bracket or supply-holder *m*, mounted on the stud *n*, to be rocked thereon when desired. An ear *o*, projecting from the portion *k* of the arm *k*, carries a stop-screw *p*, against which the face *q* of the supply-holder bears and which limits the movement of the supply-holder under the action of its projecting counterweight portion 10 *r*. The extremity *k'* of the depending arm *k*, to which the supply-holder is attached, is offset, as indicated in Fig. 8, so that the supply-holder is in line with the body of the arm *k*, bringing its spindle *l* in line with the tensions 15 *20* above and its counterweight portion *r* in such position that its movement is limited by the arm *k*, as indicated by the dotted lines in Fig. 2. The screw *p* serves not only as a stop for the supply-holder, but also as a means for adjusting the alinement of the spindle *l* with the 25 guide *f*.

The bracket *K*, which carries the yarn-controlling and supply-holding devices, is mounted on a bracket *H* in such relation to the drop-wire 26 that the thread-eye of the latter is in line with the axis on which the bracket *K* swings. The latter can then be swung into any desired position without disturbing the 30 relation between the guide *f*, the thread-line in the tension members *c* and *d*, and the drop-wire 26.

My device is operated as follows: Yarn is applied by tilting the spindle *l* forward to the position indicated by the dotted lines in Fig. 40 2.

When the yarn has been applied, the spindle is returned to its normal position by the counterweight portion *r*, limited in its movement by the stop-screw *p*. The yarn is drawn from the supply by the operator into the 45 guide *f* and laid in the tension members *c* and *d*. As it enters the guide *f* the yarn also passes into the detector *a*. From the tension members the yarn is led to the drop-wire 26 and thence to the winding mechanism. On 50 starting the winding the sudden pull on the yarn applies sufficient tension to draw it between the tension members and raise the drop-wire 26, and so quickly is the former done that the drop-wire is not only raised, but is 55 maintained in its raised position. As motes occur on the yarn they are knocked off by contact with the edges of the grid-bars. When a 60 slab occurs, it is unable to pass the slot in the detector, but engages the latter to rock it into engagement with the tension members.

The extremity 13 enters between the two members, and the inclined portion 12 forces the movable one back, relieving the yarn of its tension and permitting the drop-wire 26 to 65 fall to effect the stopping of the winding.

The detector rocks so far forward that the slab rides out of the yarn-slot, continuing its movement with the yarn until the latter stops. The operator removes the slab from the yarn in which it occurs, pieces the yarn, and proceeds with the winding. 70

By employing the devices above described a superior product is obtained. The quality of the thread is enhanced by the removal of unsightly motes—such as dirt, bits of husk, 75 &c.—by the elimination of bunches, large knots, and similar defects without entailing unnecessary waste or a large quantity of knots and by the uniform tension of the component yarns, whereby the defect known as “corkscrew” twist is overcome. This latter defect is caused by inequalities in the tension, which result in one yarn lying on the surface of the thread and following the twist about it in a spiral. It is a defect inherent in all doubling 80 processes where a pad tension is employed. The pads become worn in such manner that one yarn may receive the full degree of tension, while its neighbor, running over a worn portion, receives scarcely any. Further, a 85 pad tension is unyielding and provides no compensation for the irregularities due to drawing the yarn from the supply. The tension on the yarn is always the tension due to the pad plus the tension at the supply, increasing 90 with each increase of resistance at the supply and decreasing with diminution of resistance there. In my device the yarn-controller or tension mechanism acts as a compensator. When the tension or drag at the supply increases, 95 the tension members yield and diminish the amount of tension they apply. When the resistance at the supply lessens, increased tension is applied at the controller.

Slotted slab-stoppers have been used before, 100 but they have been secured rigidly to the machine, and their efficacy depended on breaking the yarn when a slab occurred, and thus causing the winding or other operation to be arrested. The yarn seldom or never broke at 105 or near the slab, and hence unnecessary waste was caused. Frequently it broke so close to the package wound that the broken end would run in. It was then necessary to break all the yarns, unwind them until the lost end was 110 found, and retie them all. This consumed time, inasmuch as the yarns could not be tied together in a bunch-knot, neither could they be tied separately with the knots at substantially the same point in the “doubling.” 115 Either method of tying mentioned would cause as bad or worse a defect in the finished product as would a slab. Each yarn must be tied individually and the various knots so separated in the length of the product as not 120 to materially affect its appearance.

The supply devices are particularly compact and convenient, so compact that they are brought close up to the tension devices, and are thus the more readily accessible. The 130

operator need not stoop each time the supply must be replenished. Because of its form and manner of mounting supplies of various diameters may be employed without interfering 5 one with the other.

I do not limit myself to a detector pivoted or movably secured in any special way or to any special means whereby the movement of the detector actuates the tension device, nor 10 in this connection to a tension device of any special form; nor do I limit myself to any special character of stop device or means of putting the same into action.

While the devices constituting my invention 15 have been described with particular reference to the operations of thread manufacture, they may obviously be employed in other textile work. I therefore do not limit myself to the precise form of structure hereinbefore 20 described; but

What I claim as my invention is—

1. The combination with a stopping device 25 for textile-machines in which a drop-wire is sustained by the yarn passing through it, of a detector through which the yarn first passes, and which is adapted to be moved by the engagement therewith of a slab, and means actuated by the detector to relieve the sustaining effect of the yarn, to cause said drop-wire 30 to act to effect the stopping of the machine, and allow the slab to pass by the detector without breaking the yarn.

2. The combination with a stop-motion drop-wire which, when dropped, causes the stopping 35 of the machine and which is sustained and withheld from effecting said stopping by the yarn passing through it, of a detector adapted to be engaged and moved by a slab to cause the drop-wire to fall and effect the stopping of 40 the machine without breaking the yarn.

3. The combination with a stop-motion drop-wire which, when dropped, effects the stopping 45 of the machine, but which is sustained and withheld from thus effecting the stopping by the tension of the yarn passing through it, of devices for applying and controlling the yarn tension and a detector through which the 50 yarn is drawn and which is adapted to be engaged and moved by a slab to release the tension on the yarn, and effect the stopping of the machine without breakage of the yarn, by permitting the drop-wire to fall.

4. The combination with the drop-wire of 55 a stopping device for textile-machines which, when dropped, effects the stopping of the machine but which, during the operation of the machine, is sustained and withheld from effecting such stopping by the tension of the yarn passing through it, of devices for applying and controlling said tension, comprising 60 two members pressed together by suitable means, a detector through which the yarn passes, adapted to be engaged by a slab and rocked thereby to engage and separate the 65 two tension members to release the tension on

the yarn and permit the drop-wire to fall to effect the stopping of the machine without breaking the yarn.

5. The combination with the drop-wire of 70 a stop-motion device for textile-machines, of yarn-controlling devices, comprising two tension members pressed together upon the yarn, a guide through which the yarn is drawn into the tension members, of a slotted plate intermediate the guide and the tension members, 75 having a projection of substantially triangular shape, so formed that, when the plate is rocked by a slab, the said extension enters between the members aforesaid and separates them to relieve the yarn of its tension, and when the 80 slab has passed the detector, the latter is returned to its normal position by the reclosing of said members.

6. The combination of a yarn-controlling 85 device of two members adapted to be pressed together to put tension on the yarn, of a swinging slotted plate adapted to be moved by a slab to engage and separate said members to relieve the yarn of its tension in the manner and for the purposes substantially as de- 90 scribed.

7. The combination in a yarn-controlling device having two tension members adapted to be pressed toward each other, of a guide mounted on two legs adjacent the tensions, 95 with a swinging plate, mounted between said legs on a pin passing through the legs, having a narrow slot of just sufficient width to be engaged by a slab to be rocked and caused to engage and separate said tension members, to 100 release the tension on the yarn.

8. The combination with the stop-motion drop-wire 26 of two yarn-tension members *c* and *d*, one fixed, the other mounted to be swung and pressed against the fixed member, 105 and both so flared at their outer edges as to form a guide to direct the yarn to its proper position between the members, a swinging slab-detector *a*, formed with a projection 12 to engage the movable tension, whereby when the slab-detector is rocked toward the tension members, the movable member is separated from the fixed one, and when the movable member is swung toward the fixed member, the slab-detector is returned to its nor- 110 mal position.

9. The combination with a stop-motion drop-wire 26, of two tension members, one, *d*, fixed, and the other, *c*, mounted to be swung and pressed against the fixed member, and both 115 formed to diverge from each other at their outer edges, to serve as a guide for the yarn in threading, a guide *f* through and over which the yarn passes as it enters the tensions, a swinging slotted slab-detector *a* mounted to 120 normally stand against the guide *f*, and with a projection 12 engaging the swinging tension member whereby, when the slab-detector is rocked, the swinging tension member *c* is separated from the fixed tension member *d* in 125 130

the manner and for the purpose substantially as described.

10. A yarn-controller comprising two tension members of grid form, with the bars of one member alternating with the bars of the other, and with a thread-groove cut transversely across the bars of one or both members.

11. A yarn-controller comprising two tension members, each having a portion of grid form and a curved guide portion, one member fixed and the other movable to and from the fixed member, and having an arm by which it is swung toward the fixed member, and one or both members having a thread-groove cut transversely across the bars of the grid portion.

12. A movable tension member for a yarn-controller comprising in one piece a flat grid portion, two ears turned at right angles to said grid portion, having holes to receive a rod and so formed that the axis of the rod lies in the plane of the face of said grid portion, a guide portion curved backward from the face of said grid portion, and an arm to which weight is applied to actuate the tension substantially as described.

13. A fixed tension member for a yarn-controller comprising in one piece, a flat grid portion, two ears turned at right angles to said grid portion, having holes to receive a rod and so formed that the axis of the rod lies in the plane of the face of said grid portion, a guide portion curved backward from the face of said grid portion, and an ear whereby the member is secured from turning on said rod, substantially as described.

14. In a yarn-controller, the combination with the drop-wire of a stop-motion mechanism having an eye or guide through which the yarn passes, of a bracket mounted to be swung about an axis in line with the eye of said drop-wire, separable tensions mounted on the top of the bracket, and a tilting supply-holding device mounted at the bottom of the bracket.

15. In a yarn-controller, the combination with the drop-wire of a stop-motion mechanism having an eye or guide through which the yarn passes, of a bracket mounted to swing on an axis that is in line with the eye of the drop-wire, separable tension members mounted on the top of the bracket, a guide through which the yarn is conducted to the tensions, a detector between the guide and the tensions adapted to be engaged by a slab to open the tensions, and to be rocked to allow the slab to pass on, and after it has passed, then to be returned to its normal position by the reaction of the tension members, and a counterweighted supply-holding device mounted at the bottom of said bracket, substantially as described.

16. A bracket K for a yarn-controller, adapted to be swung about a substantially vertical axis, bearings at the top for tension

and guiding devices, a depending arm curved forward at its bottom and having its extremity k' offset, and at said extremity, a bearing for the stud n and an ear for an adjustable stop-screw p, a supply-holder m mounted to be rocked on said stud, having a face q opposed to the stop-screw p, and a counterweight portion r to hold the face q against said stop-screw, and a supply-holding spindle l secured in said supply-holder, substantially as described.

17. The combination with the bracket K for a yarn-controller, having bearings at its top for separable tension members and yarn-guiding devices, and a depending arm having its extremity k' offset, and at said extremity an ear o, a stop-screw p in said ear, a bearing for a stud n, a counterweighted supply-holder m mounted on the stud and susceptible of being rocked but limited in its movement in one direction by the contact of the counterweight portion r with the arm k of the bracket K, and in the other direction by its contact with the adjustable stop-screw p, and a spindle l adapted to be adjusted in its alinement with the entrance to the tensions by said stop-screw.

18. A yarn-controlling device, comprising with a bracket K, having at its top two projections, 16 and 17, and at its bottom a depending arm k, a rod 18 mounted in the two projections and, mounted on said rod, two separable tension members c and d, each having a portion of grid form, with the bars of one member alternating with those of the other, and a thread-groove cut transversely across the bars of one or both members and means for pressing the two members together, a guide f mounted in the projection 16, with the eye of said guide and the top of the projection 17 in line with the thread-groove in the bars of the tension members, a counterweighted supply-holder m pivotally mounted at the bottom of the arm k, a spindle l in said holder to retain the yarn-supply, and a stop-screw p to limit the movement of the supply-holder and aline its spindle with the entrance to the tension members, substantially as described.

19. A slab-detector for a yarn-controller, having two ears 10, 10, a slot 11, and a substantially triangularly-shaped projection 12.

20. A slab-detector for a yarn-controller, with two separable tension members, having two ears, 10, 10, a slot 11, and a projection 12, so formed that, when the detector is moved toward the two members, the projection 12 enters between and separates them, and, when the two members of the controller are brought together, the detector is returned to its normal position.

21. A slab-detector for a yarn-controller, having two ears, 10, 10, a yarn-slot 11, with flared opening to readily receive the yarn, and a projection 12 to engage the separable mem-

bers of a yarn-controlling device, so formed that when the detector is rocked by engagement with a slub, it opens said separable members, and when the slub has passed the detector, the reclosing of said members forces the detector back to its normal position.

22. A slub-detector for a yarn-controller, having two ears 10, 10, a yarn-slot 11, with flared opening to readily receive the yarn, a projection 12 formed at an angle with the body of the detector, and having an extremity 13 formed at substantially right angles to the body of the detector, and adapted to enter between the two members of a yarn-controlling device, to engage the inclined portion 12 in the manner and for the purpose, substantially as described.

23. The combination in a yarn-controlling device of two tension members, each comprising in one piece parallel lateral bars and portions whereby the member is pivotally mounted, and in such manner that the bars of one member alternate those of the other, and means to yieldingly press a running thread between said bars to sinuate the path of the yarn as described.

24. The combination in a yarn-controlling device, of two tension members each comprising in one piece, parallel lateral bars, with a thread-groove cut transversely across them, portions whereby the member is pivotally mounted and in such relation to its mate that the bars of one member alternate with those of the other, and means whereby the members are so pressed together that a thread running through the thread-groove of the bars is diverted from its straight course to follow a sinuous path of travel.

25. The combination with the stop device of 40 a textile-machine, and with the drop-wire thereof supported by the thread, of a tension

device, and a detector adapted to be moved by engagement with a slub, and constructed to actuate the tension device to thereby relieve the tension, substantially as described.

26. The combination with two separable tension members, of a detector adapted to be moved by the engagement of a slub therewith, thereby to cause the separation of the tension members.

27. A slub-detector, constructed for pivotal connection and provided with a thread-groove and projection for actuating a tension device, substantially as described.

28. The combination in a yarn-controlling device, of two tension members each comprising in one piece parallel lateral bars, with a thread-groove cut transversely across them, portions whereby the member is pivotally mounted and in such relation to its mate that the bars of one member alternate with those of the other, and means whereby the members are so pressed together that a thread running through the thread-groove of the bars is diverted from its straight course to follow a sinuous path of travel.

29. A yarn-controller, comprising two members pressed yieldingly toward each other, each having portions which alternate and cooperate with similar portions on the other, to sinuate the yarn as it travels between the members, said portions of one or both members having formed across them a groove or guide-way for the yarn.

In testimony whereof I have signed my name to this specification in the presence of two subscribing witnesses.

SIMON W. WARDWELL.
